POTATO MASHER

James L. Hvale, Chicago, Ill., assignor to Flambeau
Plastics Corporation, a corporation of Wisconsin

Filed June 4, 1965, Ser. No. 85,568

Term of patent 14 years

(Cl. D44—29)

I claim:

The ornamental design for a potato masher, substantially as shown.
